UNITED STATES PATENT OFFICE.

FRANCIS SCHAEFFER, OF MOHNTON, PENNSYLVANIA.

HAT-FELTING MACHINE.

Application filed December 26, 1924. Serial No. 758,117.

This invention relates to improvements in felting machines of the character in which the material to be felted is confined between rollers which moisten and exert pressure on the material.

The primary object of the invention is to provide a felting machine of this type in which one of the rollers is formed in a plurality of sections, means being provided to alternately raise and lower said sections to permit the same to pound the material.

A further object of the invention is to provide means whereby the operator may simultaneously raise all of the sections of the sectional roller to permit the material to be placed between and to be removed from the rollers.

Another object of the invention is to furnish a machine of this character with adjustable means to vary the alternate raising and lowering of the sections of the sectional roller, whereby the force of the pounding action may be regulated.

With the foregoing objects outlined and with other objects in view which will appear as the description proceeds, the invention consists in the novel features hereinafter described in detail, illustrated in the accompanying drawings and more particularly pointed out in the appended claims.

Referring to the drawings:

Figure 1 is a longitudinal vertical sectional view of the apparatus taken on line 1-1 of Fig. 4.

Fig. 2 is a side view of the same.

Fig. 3 is an elevation of the opposite side of the machine.

Fig. 4 is a top plan view.

The machine comprises a frame 5 supporting a tank 6 to contain water or the like, and a heating coil 7 may be arranged in this tank to heat the water and generate steam.

In the present machine, the rollers 8 and 9 form the bed for the material to be felted and the axes of these rollers are stationary. The roller 9, as shown, is of larger diameter than the rollers 8 and it dips in to the water in the tank for the purpose of directly applying moisture to the material undergoing treatment.

Each of these rollers has a driven shaft which is journaled in the sides of the frame

and all of the rollers are driven in the same direction by gears 11 mounted on the ends 55 of the shafts and meshing with idle gears 12. These gears are driven from the main pivot shaft 13, and they are preferably covered by a casing 14.

The shaft 13 supports a plurality of arms 60 14 which are pivotally mounted on the shaft and carry the sections 15 of the sectional pressure roll at the forward ends. These sections 15 are arranged to be raised and lowered into the space 16 between the bed 65 rollers, so as to pound the material confined between the rollers. Each section 15 of the pounding roller is positively driven from the shaft 13 by means of bevel gears 17, 18, a shaft 19 and bevel gears 20, 21, and the 70 construction is such that each section 15 is continuously driven regardless of the position of the arm 14 relatively to the shaft 13.

As stated above, the sections 15 of the pounding roller are alternately raised and 75 dropped and to cause this movement, each arm 14 is provided with a tail-piece or lug 22 which are struck by oppositely extending cams 23 fixed on a rotatable shaft 24. This shaft, as best shown in Fig. 2, is provided 80 at one end with a worm gear 25 driven by a worm 26 on a shaft 27, the latter having a bevel gear 28 meshing with the gear 17. The parts 24, 25, 26, 27 and 28 are mounted in a frame 29 which is pivoted on the shaft 13, 85 so that the shaft 24 may be swung relatively to the shaft 13 to bring the cams 23 toward or move the same away from the lugs 22, and due to this construction the extent of the raising of the sections 15 of the pounding 90 roller may be varied.

As best shown in Fig. 1, the pivoted frame 29 is provided with fixed quadrant racks 30 each of which meshes with a gear 31 fixed on a shaft 32. As shown in Fig. 3, the shaft 95 32 is provided at one end with a fixed gear 33 that meshes with a worm 34 on the shaft 35, which carries a hand wheel 36. It is obvious that when the hand wheel 36 is turned, the worm 34 will actuate the shaft 100 32 and this will cause the gears 31 to move the quadrants 30 and rock the pivoted frame 29, so that the shaft 24 will be shifted, and its cams 23 will be brought to a desired position for striking the tail-pieces 22.

As mentioned above, both sections 15 of

the pounding roll may be simultaneously raised when desired, and to accomplish this result, the shaft 13 carries a swinging lever 37, the forward end 38 of which extends beneath both arms 14. From Fig. 1 it may be seen that if the lever 37 is swung in a counter-clockwise direction, the end 38 of the lever will press upwardly against both arms 14 and raise these arms to a position 10 where the roller sections 15 will not interfere with the placing of the material between the rolls. To permit the roller sections 15 to be controlled manually, the lever 37 is connected to a link 38^a which pivotally engages a second lever 39 fixed on a rock shaft 40. The latter, as best shown in Fig. 3, is provided at its outer end with a gear 41 meshing with a worm 42 on a shaft 43 having a hand wheel 44. It is evident that 20 when the wheel 44 is rotated in the proper direction, the worm 42 will cause the shaft 40 to move and swing the lever 39, and that this lever will cause the lever 37 to rock and raise both arms 14.

25 It is believed from the foregoing, that the construction, operation and advantages of the invention may be readily understood, and it is apparent that changes may be made in the details disclosed without departing 30 from the spirit of the invention as expressed in the claims.

While the rolls 15 are described as employed in pounding the material, it is obvious that they may be also employed as 35 simple rotating rolls resting upon the material in space 16 and acting on same jointly as would a single roller, the cams 23 in such case being moved by hand wheel 36 so as to entirely clear the tail pieces 22; such 40 selective rolling and pounding actions greatly increasing the capacity and usefulness of my improved construction for a great variety of work.

What is claimed and desired to be secured 45 by Letters Patent is:

1. In a felting machine, driven bed rollers and a pounding roller between which the material is to be confined, said pounding roller being of sectional formation, and 50 means for raising and lowering the sections of the pounding roller.

2. In a felting machine, driven bed rollers and a pounding roller between which the material is to be confined, said pounding roller being of sectional formation, and means for alternately raising and lowering the sections of the pounding roller.

3. In a felting machine, bed rollers and a pounding roller between which the material 60 to be felted is confined, means for driving the bed rollers, said pounding roller being of sectional formation, and means for alternately raising and lowering the sections of the pounding roller.

4. In a felting machine, bed rollers and

a pounding roller adapted to confine the material to be felted, means for rotating each of said rollers, said pounding roller being of sectional formation, and means for alternately raising and lowering the sections 70 of the pounding roller.

5. In a felting machine, driven bed rollers and a sectional pounding roller adapted to confine the material to be felted, pivotally mounted arms carrying the sections of the 75 pounding roller, and means for alternately raising and lowering said arms.

6. In a felting machine, driven bed rollers and a sectional pounding roller, pivotally mounted arms carrying the sections of the 80 pounding roller, a lug connected to each arm, and means engageable with said lugs for causing alternate raising and lowering of said arms.

7. In a felting machine, rotated supporting rollers for the material to be felted, a sectional pounding roller adapted to pound the material carried by the supporting means, and means for alternately raising and lowering the sections of the pounding roller. 85

8. In a felting machine, driven bed rollers and a sectional pounding roller adapted to confine the material to be treated, pivotally mounted arms carrying the sections of the pounding roller, tail-pieces fixed to 90 said arms, and cams engageable with said tail-pieces for alternately raising and lowering the arms.

9. In a felting machine, bed rollers and a sectional pounding roller adapted to confine the material to be felted, pivotally mounted arms carrying the sections of the pounding roller, tail-pieces fixed to said arms, cams engageable with the tail-pieces 100 for raising and lowering said arms, a shaft carrying the cams, and means for shifting said shaft around the axis about which the arms move.

10. In a felting machine, supporting means adapted to carry and move the material to be felted, a sectional pounding roller cooperating with the supporting means and adapted to pound the material so supported, pivotally mounted arms carrying the sections of the pounding roller and 115 provided with projections, cams engageable with said projections for raising and lowering the sections of the pounding roller, a shaft carrying said cams, a rocking frame carrying the shaft, and toothed means for shifting said frame to move the cams toward and away from said projections. 120

11. In a felting machine, supporting means adapted to carry and move the material to be felted, a pounding roller cooperating with said means for pounding the material so supported, arms carrying said roller, a shaft about which said arms rock, 125 projections fixed to the arms, cams adapted to engage said projections for raising the 130

arms, a second shaft carrying said cams, and means for shifting the second shaft relatively to the first shaft to vary the contact between the cams and said projections.

5 12. In a felting machine, driven bed rollers, and driven sectional rollers movable into and out of operative relation with said

bed rollers, selective means to alternately or jointly raise and let fall said sectional rollers.

10 In testimony whereof I affix my signature.

FRANCIS SCHAEFFER.
